UNITED STATES PATENT OFFICE

2,534,578

VACUUM CLEANER

Silas F. Crabb, Des Moines, Iowa

Application September 2, 1947, Serial No. 771,623

4 Claims. (Cl. 183—55)

1

The principal object of this invention is to provide a vacuum cleaner of the bagless type, wherein the dirt and air separating filter is flat and horizontal so that dirt and like will have a tendency to fall, by gravity, downwardly and free of the filter means.

A further object of my invention is to provide a vacuum cleaner having a flat horizontal internal filter fabric that is capable of being periodically electrically vibrated from a point inside the clean air compartment, thereby driving and forcing any dirt accumulation that may have gotten into the filter backwardly in the direction from whence it came and into the dirt receiving compartment.

A still further object of this invention is to provide a vacuum cleaner that may obtain and retain a great quantity of dirt and like without interfering or effecting the efficiency of the same.

A still further object of my invention is to provide a vacuum cleaner that is easily and quickly cleaned.

A still further object of my invention is to provide a vacuum cleaner that has all working parts easily accessible for inspection or repair.

A still further object of this invention is to provide a vacuum cleaner that is refined in appearance, economical in manufacture, and durable in use.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of my vacuum cleaner ready for use.

Fig. 2 is a longitudinal sectional view of my vacuum cleaner and more fully illustrates its construction.

Fig. 3 is a cross-sectional plan view of the device, taken on line 3—3 of Fig. 2.

Fig. 4 is a perspective view of one end portion of the filter and vibrating means.

Fig. 5 is a cross-sectional view of my vacuum cleaner, taken on line 5—5 of Fig. 2.

Most vacuum cleaners are of the bag type, wherein all dirt and air is forced into one end of the bag. Obviously, almost immediately as the bag fills with dirt the efficiency of the machine decreases. This is due to the dirt tending to fall, by gravity, directly into the path of the dirt and air entering the end of the bag.

2

As a matter of fact, a good part of the air must pass through the dirt and material collected in the bag. All fabric filter means is also prone to clog up with fine dirt. In the bag type of vacuum cleaner it is entirely impracticable and undesirable to agitate the bag within the room being cleaned, inasmuch as a lot of this fine dust will pass through the bag walls and settle in the room being cleaned. I have overcome such objections by providing an internal fabric filter that permits the heavier dirt and material to fall, by gravity, away from it and also by providing a mechanical agitating or beating means inside the vacuum cleaner and above the filter means.

Referring to the drawings, I have used the numeral 10 to designate the upper shell of my device and the numeral 11 to designate the lower shell. These two shell portions are detachably secured together by any suitable means such as fasteners 12. A continuous band 13 is secured to the lower portion of the member 10 and which overlaps the upper portion of the member 11, as shown in Fig. 2. Resilient gaskets 14 may be secured to and placed between the lower marginal edge of the member 10 and the upper marginal edge of the member 11. Wheels 15 are secured to the member 11 to facilitate the movement of the machine in use. The numeral 16 designates my flat filter fabric having its marginal edge portions secured around a frame 17, as shown in Fig. 4. As the members 10 and 11 are of rectangular construction, this filter means is also of rectangular form and is placed between the members 10 and 11, as shown in Fig. 2. If, for any reason, it is desirable to remove this filter means, it is merely necessary to detach the portion 10 from the portion 11 and remove the same. It can be as easily replaced. However, due to the agitating means, later explained, there will be indeed little reason for the removal of the filter screen and it will normally remain by friction within the portion 11 when the portions 10 and 11 are separated from each other. This screen 16 separates the inside of the portion 10 from the inside of the portion 11 and therefore provides a dirt compartment 18 and a filtered air compartment 19. The numeral 20 designates the intake opening in the forward end of the portion 10 and designed to be connected to the usual attachment hose 21. This opening 20 communicates with an air-tight passageway 22 which passes downwardly and through an opening in the filter screen. By this construction, dirt and air drawn into the device

will pass into the compartment 18 and below the screen 16. The numeral 23 designates an ordinary electric motor and suction fan mounted in the inside top of the portion 10, as shown in Fig. 2. The numeral 25 designates electric lead wires electrically connected to the suction motor through the ordinary toggle switch 24. The numeral 35 designates an exhaust port through the top center of the member 12 communicating with the outside atmosphere and the inside of the motor fan. By this arrangement, when the motor and fan 23 are running, the air and dirt will be pulled through the hose 21, through the passageway 22, into the dirt compartment 18, and then upwardly through the filter screen 16. At this point, the dirt and air will be separated with the dirt normally falling to the bottom of the member 11 and clear of the under side of the filter means 16. The filtered air will then move upwardly into the compartment 19 and thence through the fan means and out of the port 35. By the filter means being flat and horizontal it not only lends itself to mechanical agitation from above, but does provide a wide area through which the air may pass. Dirt falling downwardly by gravity into the bottom of the member 11 will be free of the oncoming dirt and air and this oncoming dirt and air is encouraged to completely avoid and pass over the accumulated dirt already in the machine by the horizontal shelf 26 directly below the passageway 22 and above the extreme bottom of the member 11. As herebefore noted, however, any filter means may become impregnated with fine dust and have its efficiency effected. To eliminate this problem, I have provided an agitating or beating means inside the shell 10 and above the filter means 16. This portion of the device consists mainly of bearing members 27 and an elongated crank shaft 28 journaled therein and extending along the longitudinal center length of the top of the filter means 16. This compound crank shaft, when rotated, strikes cleats or like members 29 secured to the top of the filter fabric, as shown in Fig. 5. Obviously, when the shaft 28 is rotated at good speed the action will be that of the beating of the dirt out of the filter fabric similar to that of the manual beating of a rug. As this beating takes effect above the filter the tendency will be to drive the fine dust, aided by gravity, back in the direction it originally penetrated the fabric and downwardly into the bottom of the dirt compartment 18. The numeral 30 designates a sprocket gear on one end of the shaft 28. The numeral 31 designates a small electric motor mounted inside the member 10 and operatively connected to the spur gear 30 by the chain 32. This motor is grounded and connected to the electric lead wires 25 through the push switch 33. By this arrangement, when it becomes necessary to clean the fabric 16 it is merely necessary to push downwardly on the switch 33, thereby electrically connecting the motor 31 and rotating the beating and agitating crank shaft 28. As the screen is inside the machine the cleaning of the screen will not deposit dust within the room being cleaned. However, it is important that the screen be flat and horizontal with the agitating means above the screen. From my experiments, I have found that if the beating means were placed below the filter screen the tendency would be to drive the dirt through the screen and into the room. Only by using the

flat screen and placing the agitating means above the screen was I able to accomplish the desired results. The numeral 34 designates a handle means on the top of the member 10. This handle means consists chiefly of an elongated horizontal rod and two upwardly extending posts hinged at their lower ends to the top of the case and their upper ends secured to the horizontal bar at some distance from its two ends to provide a simple means for receiving and holding the wrapped electric lead wire.

Some changes may be made in the construction and arrangement of my improved vacuum cleaner without departing from the real spirit and purpose of my invention, and it is my intention to cover by my claims, any modified forms of structure or use of mechanical equivalents which may be reasonably included within their scope.

I claim:

1. In a vacuum cleaner, a bottom shell container, an inverted top shell container, a means for detachably securing said two shell containers together, a flat flexible horizontal filter means between said two shell containers; said filter provided with a plurality of spaced apart cleat members, a dirt and air inlet passageway terminating vertically below said filter means and inside said bottom shell container, a horizontal shelf baffle means inside said bottom container and spaced directly below the outlet end of said dirt and air passageway, a suction fan inside said inverted top shell container and communicating with the outside atmosphere, and a motor operatively connected to said fan; agitating means operatively associated with said cleat members and a motor operatively associated with said agitating means.

2. In a vacuum cleaner, a bottom shell container, an inverted top shell container, a means for detachably securing said two shell containers together, a flat flexible horizontal filter means between said two shell containers; said filter provided with a plurality of spaced apart cleat members on the top surface thereof, a dirt and air passageway communicating with the inside of said bottom shell container, a suction fan inside said inverted top shell container and in communication with the outside atmosphere, a motor operatively connected to said fan, bearing members, a crank shaft rotatably mounted in said bearing members above said filter means and capable of striking and agitating said cleat members when rotated, and a motor inside said inverted top shell container and operatively connected to said crank shaft.

3. In a vacuum cleaner, a bottom shell container, an inverted top shell container, a means for detachably securing said two shell containers together, a flat flexible horizontal filter means between said two shell containers, a dirt and air passageway communicating with the inside of said bottom shell container, a suction fan inside said inverted top shell container and in communication with the outside atmosphere, a motor operatively connected to said fan, protective cleats on the upper side of said filter means, a crank shaft rotatably mounted in said inverted top shell container and capable of striking said cleats when rotated, and a motor operatively connected to said crank shaft.

4. In a vacuum cleaner, a bottom shell container, an inverted top shell container, a means for detachably securing said two shell containers together, a flat flexible horizontal filter

means between said two shell containers, a dirt and air passageway communicating with the inside of said bottom shell container, a suction fan inside said inverted top shell container and in communication with the outside atmosphere, a motor operatively connected to said fan, protective cleats on the upper side of said filter means, a crank shaft rotatably mounted in said inverted top shell container and capable of striking said cleats when rotated, a motor operatively connected to said crank shaft, a handle means on the top of said upper shell comprising two spaced apart vertical posts hingedly secured to the top of said upper shell and a horizontal bar secured at each respective end to one of said posts; said handle member designed to be encircled by the electric cord on said device at times.
